UNITED STATES PATENT OFFICE.

CHARLES WAINWRIGHT, OF ERIE, PENNSYLVANIA.

UNLOADING SYSTEM.

1,180,213.

Specification of Letters Patent. Patented Apr. 18, 1916.

Application filed May 2, 1912, Serial No. 694,690. Renewed March 11, 1916. Serial No. 83,690.

To all whom it may concern:

Be it known that I, CHARLES WAINWRIGHT, a citizen of the United States, residing at Erie, in the county of Erie and 5 State of Pennsylvania, have invented new and useful Improvements in Unloading Systems, of which the following is a specification.

The general object of the invention is to 10 refine the present systems of unloading fluid compressors and particularly those systems shown in my co-pending applications, Serial Numbers 646349 filed August 28, 1911 and 666946 filed December 20, 1911. The former 15 of these systems consists of a plurality of choking controllers arranged so as to operate successively with successive predetermined increasing pressures in the receiver of the compressor to close the intakes of the 20 compressor. With this arrangement a considerable amount of negative work is thrown onto the pistons, this negative work resulting from the piston or pistons attenuating the air entrapped between the controllers and the cylinders as the controllers 25 go into operation. In the latter of the above named applications provision is made for the air entrapped by the going into action of the choking controller to escape into the 30 atmosphere or source of fluid supply. But this system as designed, can only work with a choking controller. Therefore the system is in a measure complex. With the present invention, however, the choking controller 35 is eliminated and the interior of the cylinder is placed in communication with the source of fluid supply upon a predetermined pressure in the receiver of the compressor. Moreover, provision is made for balancing 40 the load on the high and low pressure pistons of a multiple stage compressor, when the invention is used in connection with such a device, as the various unloaders go into operation.

45 Other objects will appear and be better understood from that embodiment of the invention of which the following is a specification, reference being had to the accompanying drawings forming a part hereof, and in which:

Figure 1 is a plan view of a multiple stage compressor with my invention applied thereto. Fig. 2 is a side elevation of Fig. 1. Fig. 3 is an end elevation. Fig. 4 is a 55 vertical cross section taken approximately on the line 4—4 of Fig. 1. Fig. 5 is a dia-

grammatic view of the invention. Fig. 6 is a detail horizontal section showing the unloader in applied position. Fig. 7 is a detail section on the line 7—7 of Fig. 6. 60

In the drawings and especially in Figs. 1 to 3 inclusive, *a* indicates generally the compressor which is of the double acting multiple stage type. The pistons (not shown) in the low pressure cylinders *b* and 65 high pressure cylinder are suitably connected to a motor *d* of any preferred type adapted for operating the said pistons. An inter-cooler *e* is suitably connected such as by pipes *f*—*f* to the high and low pressure 70 cylinders *c* and *b* between which it is herein shown as interposed. The high pressure side of the compressor rests upon a base *g* and a suitable base *h* forms a bed for the low pressure side and the intake box *i*. 75

The foregoing is descriptive of a well known type of compressor and it must be understood that in the application of my invention about to be described, I do not intend to limit myself to a compressor 80 wherein the parts are disposed as previously described or a compressor of the type set forth.

The opposite ends of each of the cylinders *b* and *c* have lateral ports 5 arranged adjacent to the heads of the cylinders as shown in detail in Fig. 6. In each of such ports is fitted, as shown in Fig. 6, a valve seat in the form of a spider 8 which is adapted for guiding the stem 9 fitted at one end with 85 a valve 10 which controls the port 5. The casing 11 which is suitably connected with the valve seat is apertured as at 12—12 to permit the air to pass to the source of supply when the valve is unseated. 90

95 Since the underlying principle of my invention resides in placing the interior of the cylinder in communication with the source of fluid supply upon a predetermined pressure in the receiver of the compressor, it 100 matters little in so far as the broad principle is concerned whether the air passes directly into the atmosphere or is suitably conveyed to any desired part of the compressor. For the purpose of refining the structure however, in point of noiselessness, I 105 form each cylinder with a chamber 13 extending substantially to the length of the cylinder and communicating through a nipple 14 with the intake box *i*. The upper 110 portion of this chamber is, as shown in Fig. 6, tapped near one end to receive the casing

11, it being understood that the opposite end of the chamber is similarly adapted for receiving the structure for unloading that end of the cylinder. A flange 15 on the casing 5 11 forms a stop which limits the inward movement of the casing into the cylinder and also provides a means through which bolts or other fastening elements may be passed, when the flange is apertured, to secure the casing to the cylinder. A cap or bonnet 16 is suitably fastened to the outer end of the casing 11 and has a guide 17 for the rod 18 which carries at its inner end a plunger 19. The valve stem 9 has a reduced 10 portion 20 that passes through an axial bore in the rod 18 and plunger 19 and which is held against displacement by a nut 21 and the shoulder 22. A spring 23 is employed for holding the valve 10 to its seat and the plunger 19 clear of a lateral port in the casing 8 which receives one end of a pipe 24. The outer face of the plunger 19 has a groove 25 which increases the volume or space between the bonnet and the outer face 20 of the plunger so that the compressed fluid entering the space will more readily act on the plunger.

Referring now to Fig. 5 the header 26 connects with any suitable point in the receiver 30 (not shown) of the compressor and extends along the low pressure side of the compressor and connects by branch pipes 27—27 to a series of controllers 28 of any desired type. The controllers are so disposed and 35 connected to the unloaders as to bring about the unloading of two alternate ends of the low pressure cylinders successively and to effect the unloading of the other two ends of the said cylinders successively and synchronously with the unloading of the high pressure cylinder.

With the parts arranged as shown in Fig. 5, and each controller adjusted so as to operate with a receiver pressure different from the receiver pressure which operates any other controller the unloading of the compressor may be effected as above indicated. For instance, if the controller marked *k* 45 operates with the least amount of container pressure previously determined upon, then when such pressure has been obtained in the pipe 27 and chamber 29 in Fig. 6, the plunger 30 will move outwardly and unseat the needle valve 31. The compressed fluid will 50 now enter the pipe 24 and the chamber afforded by the groove 25 and cap 16. Inasmuch as the spring 23 is relatively weak, the plunger will be moved inwardly by the pressure in the chamber, and carry the valve 55 10 into the counterbored portion 32 of the port 5. Thus the air drawn into the cylinder by the piston on its suction stroke, will, upon the compression stroke of the piston, be discharged through the port 5. With the 60 second controller marked *m* adjusted to op-

erate with a container pressure different from that which operated the controller *k*, then upon the going into operation of the controller *m* the opposite end of the cylinder will be unloaded and at the same time and 70 by virtue of a pipe connection 33 between the controller *m* and the unloader in one end of the high pressure cylinder, the said end of the high pressure cylinder will be unloaded synchronously with the unloading of the 75 low pressure cylinder. This construction establishes equilibrium in the high and low pressure pistons which are active after the unloading of one of the low pressure cylinders.

The going into action of the controller marked *n* effects the unloading of one end of the second low pressure cylinder and when the highest predetermined pressure operates the controller *o* the complete unloading of 85 the compressor is obtained since the last unloader which goes into operation on the low pressure side of the compressor is connected with the controller *o* and the other unloader of the high pressure cylinder by a pipe 34. 90

What I claim as new is,—

1. A plural stage fluid compressor comprising a trinity of compressor cylinders in one of which the final stage of high compression takes place, in two compression 95 chambers and in the others the initial stage of low compression takes place in four compression chambers, means for effecting compression in the compression chambers of the cylinders, an unloading valve located in 100 each compression chamber of each cylinder, a fluid pressure passage way connecting one unloading valve of one cylinder of initial compression with one unloading valve of the cylinder of final compression, a fluid 105 pressure passage way connecting one unloading valve of the other cylinder of initial compression with the other unloading valve of the cylinder of final compression, pressure operated valves connected one with 110 each of the unloading valves of the cylinders of initial compression for controlling the passage of fluid pressure to the unloading valves, and means for supplying fluid pressure to all of the pressure operated 115 valves from a single source.

2. A plural stage fluid compressor comprising a trinity of compressor cylinders in one of which the final stage of high compression takes place in two compression 120 chambers and in the others the initial stage of low compression takes place in four compression chambers, means for effecting compression in the compression chambers of the cylinders, an unloading valve located in 125 each compression chamber of each cylinder, a fluid pressure passage way connecting one unloading valve of one cylinder of initial compression with one unloading valve of the cylinder of final compression, a fluid 130

pressure passage way connecting one unloading valve of the other cylinder of initial compression with the other unloading valve of the cylinder of final compression, pressure operated valves connected one with each of the unloading valves of the cylinders of initial compression for controlling the passage of fluid pressure to the unloading valves, said pressure operated valves being adjusted to operate at different times and when subjected to different pressures, and means for supplying fluid pressure to all of the pressure operated valves from a single source.

15 3. A plural stage fluid compressor comprising a trinity of compressor cylinders in one of which the final stage of high compression takes place in two compression chambers and in the others the initial stage 20 of low compression takes place in four compression chambers, means for effecting compression in the compression chambers of the cylinders, an unloading valve located in each compression chamber of each cylinder,

a fluid pressure passage way connecting one unloading valve of one cylinder of initial compression with one unloading valve of the cylinder of final compression, a fluid pressure passage way connecting one unloading valve of the other cylinder of initial compression with the other unloading valve of the cylinder of final compression, pressure operated valves connected one with each of the unloading valves of the cylinders of initial compression for controlling the passage of fluid pressure to the unloading valves, said pressure operated valves being adjusted to operate successively when subjected to fluid pressure which increases in the degree of compression, and means for supplying fluid pressure to all of the pressure operated valves from a single source.

In testimony whereof I have affixed my signature in presence of two witnesses.

CHARLES WAINWRIGHT.
